UNITED STATES PATENT OFFICE.

JAKOB LEVITIN AND JACOB ROSEN, OF CHICAGO, ILLINOIS.

DESIGN FOR A CLOTHES-POUNDER.

SPECIFICATION forming part of Design No. 33,037, dated July 31, 1900.

Application filed May 3, 1900. Serial No. 15,417. Term of patent 7 years.

To all whom it may concern:

Be it known that we, JAKOB LEVITIN and JACOB ROSEN, citizens of the United States, residing at Chicago, in the county of Cook and State of Illinois, have invented and produced a new and original Design for Clothes-Pounders; and we do hereby declare the following to be a full, clear, and exact description of the same, reference being had to the accompanying drawings, forming a part thereof.

This invention relates to an original design for clothes-pounders; and it is embodied in the shape and configuration hereinafter described, and illustrated in the accompanying drawings.

In the drawings the design is shown in perspective in Figure 1, and in vertical section in Fig. 2.

The design as shown consists, essentially, of a frusto-conical body portion A, an enlargement B, having oppositely-sloping walls, terminating in a cylindrical collar C at the apex of the upper wall of portion B. On the

upper sloping wall of portion B are angular 25 hoods D, spaced apart. The lower portion of the body has a diaphragm thereacross, which carries a depending protuberance E, which is inclined inwardly from opposite ends. Extending throughout this body and enlargement 30 is a tube F, terminating in a funnel-shaped end f, located in the protuberance E.

The essential features of the design are the peculiar shapes of the body and enlargement and the protuberance on the diaphragm, as 35 shown.

Having thus described the invention, what we claim as new, and desire to secure by Letters Patent, is—

The design for a clothes-pounder, substantially as shown and described.

In testimony whereof we affix our signatures in presence of two witnesses.

JAKOB LEVITIN.
JACOB ROSEN.
